UNITED STATES PATENT OFFICE.

ALPHEUS A. POOLE, OF DETROIT, MICHIGAN.

EXTENSIBLE CAR STEP.

Application filed November 28, 1924. Serial No. 752,711.

My invention relates to a new and useful improvement in an extensible car step adapted for use on passenger cars and the like to provide a step which may be moved 5 downwardly into operative position and slid upwardly out of operative position, so as to raise the step to such an elevation as to permit its passage over any obstruction which may be present on the track over 10 which it is drawn. The present invention relates particularly to automatic means for controlling the raising of this step so that when the locomotive, whether it be steam or electric, is about to be started to draw 15 the car on which the step is mounted, the step will be automatically raised to inoperative position. It is an object of this invention to provide means for raising such a step to inoperative position by the application of 20 power to the locomotive and to provide means for locking the step actuating mechanism against operation upon the withdrawal of the power from the locomotive.

Other objects will appear hereinafter.

25 The invention consists in the combination and arrangement of parts hereinafter described and claimed.

The invention will be best understood from a reference to the accompanying drawings which form a part of this specification, 30 and in which,

Fig. 1 is a perspective view of the step of a car.

Fig. 2 is a sectional view taken substantially on line 2—2 of Fig. 1.

Fig. 3 is a fragmentary side elevational view of a part of the steps.

Fig. 4 is a sectional view taken on substantially line 4—4 of Fig. 3.

40 Fig. 5 is a fragmentary side elevational view of the valve operating mechanism mounted on the locomotive and Fig. 6 is a central vertical sectional view of the valve shown in Fig. 5.

45 The invention is adapted for use particularly with cars 9 having permanently arranged steps 11 for mounting into and dismounting from the car 9. The steps 11 have side walls 12 and 13. Extension side walls 50 14 and 15 provided with longitudinally extending slots 16, 17 respectively, are adapted for mounting on the side walls 12 and 13 in slidable relation, these extensible side walls carrying an extensible step 18. The arrangement is such that the step 18 may be lowered relatively to the lower-most step

permanently arranged on the car, so as to eliminate the necessity of using a foot stool or the like in assisting passengers to mount to and dismount from the car 9. When the 60 car is in movement, the step 18 would be raised so as to engage at its upper surface with the lower-most step. Mounted on the step 18, preferably centrally thereof, and projecting rearwardly therefrom, is a bracket 65 arm 19 to which is pivotally connected one end of a piston rod 20, the opposite end carrying a piston head 21 slidable in the cylinder 22 which carries a head 23 which is mounted on the floor 24 of the car 9. Projecting from one of the steps 11 is a bracket 25 which is provided with an opening through which the piston rod 20 projects, the bracket 25, serving to guide the piston 20 in its movements and serving to afford a 70 means for connection of one end of a spring 26 which is positioned about the rod 20 in embracing relation, the opposite end of the spring 26 being connected to the bracket 75 arm 19. This spring is normally under tension so that it normally tends to retain the step 18 in close engagement with the under surface of the lower-most fixed step. The cylinder 22 is suitably connected adjacent the head 23, by piping 27 to a source of 80 steam or compressed air supply. Interposed in the piping 27 between the source of steam or air supply and the cylinder 22, is a valve 28 which is adapted to control the flow of steam or air through the piping to the cylinder 22. The valve 28 is provided with an 85 operating handle 29 which is adapted for rocking movement for operating the valve 28. Mounted in the extension side wall 14 is a box forming plate 30 having a recess 90 31 formed in its base. Engaging at one end of the recess 31 is a spring 32 the opposite end of which engages in a recess 33' formed in an arm 33 which is pivotally mounted 95 as at 34 to the side walls of the box forming portion 30. The arrangement is such that as the step 18 moves into close engagement with the lowermost step 11 the end of the arm 33 will engage the arm 29 and rock it upwardly to close the valve 28, so as to 100 close communication between the cylinder 22 and the source of steam or air supply, the extension side 14, when moving upwardly, carrying the arm 33 upwardly sufficiently to effect this.

105 In the locomotive which is used for drawing the car 9, the operator of the locomotive

is provided with a throttle lever 35, for controlling the delivery of power to the locomotive. This lever, 35, is connected by a rod 36 to a suitable control for regulating the delivery of power to the locomotive. This connection of the lever 35 to the rod 36 is a loose one, a slot 37 being provided in the end of the arm 36 to affect this loose connection. Pivotally connected to the throttle lever 35 is an arm 39 which is pivotally connected to an operating arm 40 adapted for operating the stop cock 41 which controls the flow of steam or compressed air to the piping 27 which communicates with the cylinder 22. Suitable piping 42 communicates with the source of steam or compressed air and with the valve 41'. An exhaust piping 43 also communicates with the valve 41', so that when the delivery of steam or compressed air through the piping 42 is shut off the piping 27 will be in communication with the exhaust piping 43, thus permitting an escape of the steam or compressed air from the cylinder 22 permitting the spring 20 to raise the step 18 into inoperative position.

When the train is brought to a stop the brakeman or porter of the car 9 will manually open the valve 28, the arm 33 being inwardly compressible for permitting the opening of the valve 28 by means of a downwardly rocking of the arm 29. Inasmuch as it would not be desired to lower the step 18 at any time, other than when the power is shut off from the locomotive pulling the train, the throttle lever 35, would then be moved to position which would open communication between the piping 27 and the piping 42. When the porter or brakeman would open the valve 28 the compressed air or steam, as the case may be, would enter the cylinder 22 and force the step 18 downwardly into the position shown in the drawings: In this downward movement the arm 33 would ride over the arm 29 into substantially the position shown in Fig. 3. When it is desired to move the train again, the engineer in applying the power would operate the throttle lever 35. On account of the loose connection by the throttle lever 35, and 36, the valve 41' would be so operated as to close communication between the piping 27 and the piping 42, and open communication between the piping 43 and the piping 27, thus permitting a bleeding of the cylinder 22 as the spring 26 moves the step 18 upwardly. The formation of the stop cock 41 should be such that as communication between the piping 42 and the piping 27, is closed and communication established between the piping 43 and the piping 27, a further opening movement of the rod 36 will not serve in any wise to disturb this arrangement. This could be regulated by the relative location of the various ports

around the valve cock 41, the arrangement being dependent upon the amount of movement of the throttle lever 35, applying or shutting off the power to the locomotive.

In this manner I have afforded power means for moving the auxiliary step into operative position and automatic means for raising the step into inoperative position just previously to the application of power to the locomotive for drawing the train.

While I have illustrated and described the preferred form of construction, I do not wish to limit myself to the precise details of the structure shown, but desire to avail myself of such variations and modifications as come within the scope of the appended claims.

Having thus described my invention what I claim as new and desire to secure by Letters Patent is:

1. In combination with a car adapted for being drawn by a locomotive and provided with a set of permanently arranged steps, an auxiliary step mounted beneath the lower-most of said permanent steps and adapted for slidable movement relatively thereto, into operative and inoperative position; power operating means for moving said step into operative position; power operated means for controlling the delivery of power to said power operated means; resilient means for moving said step from operative to inoperative position; and means for automatically closing said control means upon the movement of said step from operative to inoperative position.

2. In combination with a car adapted for being drawn by a locomotive and having permanently arranged steps mounted thereon, an auxiliary step slidably mounted beneath the lower-most of said permanently arranged steps and adapted for movement into operative and inoperative position; power operated means for moving said step into operative position; control means for controlling the delivery of power to said power operated means; resilient means for moving said step from operative to inoperative position; means for automatically closing said control means upon the movement of said step from operative to inoperative position; additional control means for controlling the delivery of power to said power operated means; and means for operating said additional control means for preventing the delivery of power to said first mentioned control means after the application of power to said locomotive and for opening said additional control means to permit the delivery of power subsequently to the shutting off of the power from said locomotive.

3. In combination with a car adapted for being drawn by a power driven locomotive having means for controlling the delivery

of power to said locomotive and permanently arranged steps on said car, an auxiliary step slidably mounted on said permanently arranged steps; a cylinder mounted adjacent said steps; a piston slidably mounted in said cylinder; a piston rod connected to said piston and projecting outwardly from said cylinder, the free end of said piston rod being connected to said auxiliary step, and adapted 10 for moving said step to operative position upon the delivery of power to said cylinder; resilient means for moving said steps from inoperative to operative position; piping for conducting power to said cylinder; means

interposed in said piping for controlling the 15 delivery of power to said cylinder; yieldable means for operating said control means for preventing the delivery of power to said piston upon the movement of said auxiliary step from operative to inoperative position; 20 means for controlling the delivery of power to said piping; and means for operating said last mentioned control means in relation to the delivery of power to said locomotive.

In testimony whereof, I have signed the 25 foregoing specification.

ALPHEUS A. POOLE.
